INVENTOR

DE WANE B. SMITH

By Milton E. Robinson

ATTORNEY

UNITED STATES PATENT OFFICE.

DE WANE B. SMITH, OF DEERFIELD, NEW YORK.

DESIGN FOR A PISTON-HEAD FOR PUMPS.

SPECIFICATION forming part of Design No. 33,508, dated November 6, 1900.

Application filed September 28, 1900. Serial No. 31,457. Term of patent 7 years.

To all whom it may concern:

Be it known that I, DE WANE B. SMITH, a citizen of the United States, residing at Deerfield, in the county of Oneida and State of New York, have invented and produced a new and original Design for Piston - Heads for Pumps, of which the following is a specification, reference being had to the accompanying drawings, forming a part thereof.

Figure 1 is a perspective view of a piston-head, showing my design. Fig. 2 is a sectional view of the same.

The feature of the design is the form and arrangement of the parts forming the piston-head—that is to say, the circular cup-shaped

portion 1, the outer circular plate-like part 2, and the inner circular plate-like part 3, having the projections 4.

Having described my invention, what I claim as new, and desire to secure by Letters Patent, is—

The design for a piston-head, substantially as herein shown and described.

In witness whereof I have signed my name to this specification, in the presence of two witnesses, this 25th day of September, 1900.

DE WANE B. SMITH.

Witnesses:

E. WILLARD JONES,
S. A. BROWN.
